[57] CLAIM

The ornamental design for a reel for a magnetic tape cassette, as shown and described.

DESCRIPTION

FIG. 1 is a front elevational view of a reel for a magnetic tape cassette, showing my new design;

FIG. 2 is a rear elevational view thereof;

FIG. 3 is a right-side elevational view thereof, the left side being a mirror image thereof; and

FIG. 4 is a top plan view thereof, the bottom plan view being a mirror image thereof.

FIG. 1

FIG. 2

FIG. 3

FIG. 4
